Primary Examiner — Wan Laymon*(74) Attorney, Agent, or Firm* — Armina E. Stricklin(57) **CLAIM**

The ornamental design for an oral care applicator, as shown and described.

DESCRIPTION

FIG. 1 is a perspective view of an oral care applicator, embodying the new design;

FIG. 2 is a front side view of the oral care applicator of FIG. 1;

FIG. 3 is a rear side view of the oral care applicator of FIG. 1;

FIG. 4 is a right view of the oral care applicator of FIG. 1;

FIG. 5 is a left view of the oral care applicator of FIG. 1;

FIG. 6 is a top planar view of the oral care applicator of FIG. 1; and,

FIG. 7 is a bottom planar view of the oral care applicator of FIG. 1.

The broken lines showing portions of an oral care applicator are included for illustrating environmental structure and form no part of the claimed design.
